US0D1033217S

(12) **United States Design Patent** (10) **Patent No.:** **US D1,033,217 S**
(45) **Date of Patent:** **** Jul. 2, 2024**

(54) **CONTAINER LID HAVING
NON-CONGRUENT FRUSTUM SHAPED
SIDEWALL SEGMENTS ENABLING
NESTING**

(71) Applicants: **Daniel A. Zabaleta**, Cooper City, FL (US); **Dennis Stammen**, Brookville, OH (US); **Steven Todd Albright**, Piqua, OH (US)

(72) Inventors: **Daniel A. Zabaleta**, Cooper City, FL (US); **Dennis Stammen**, Brookville, OH (US); **Steven Todd Albright**, Piqua, OH (US)

(**) Term: **15 Years**

(21) Appl. No.: **29/777,270**

(22) Filed: **Apr. 5, 2021**

CLAIM

We claim the ornamental design for a container lid having non-congruent frustum shaped sidewall segments enabling nesting, as shown and described.

DESCRIPTION

FIG. 1 is an isometric top view of a container lid having non-congruent frustum shaped sidewall segments enabling nesting;

FIG. 2 is an enlarged detail view of area 2 circumscribed within FIG. 1;

FIG. 3 is an isometric bottom view thereof;

FIG. 4 is an enlarged detail view of area 4 circumscribed within FIG. 2;

FIG. 5 is a top plan view thereof;

FIG. 6 is an enlarged detail view of area 6 circumscribed within FIG. 5;

FIG. 7 is a bottom plan view thereof;

FIG. 8 is an enlarged detail view of area 8 circumscribed within FIG. 7;

FIG. 9 is a front view thereof;

FIG. 10 is a side view at 45 degrees to the left from the front view thereof;

FIG. 11 is a left side view thereof;

FIG. 12 is a rear view thereof;

FIG. 13 is a right side view thereof;

FIG. 14 is a sectioned elevation left side view thereof, the section being taken in a direction of section line 14-14 of FIG. 5;

FIG. 15 is an enlarged detail view of area 15 circumscribed within FIG. 14;

FIG. 16 is a sectioned elevation 45 degree to the left from the front side view thereof, the section being taken in a direction of section line 16-16 of FIG. 5;

FIG. 17 is an enlarged detail view of area 17 circumscribed within FIG. 16;

FIG. 18 is a sectioned elevation left side view thereof, the view illustrating an exemplary nesting capability thereof;
